CLAIM

The ornamental design for a leash housing, as shown and described.

DESCRIPTION

FIG. 1 is an isometric view of a leash housing in accordance with the new design, the figure showing a gate closed and with leash gate lock in a locked position, with an optional stop button integrated with a larger optional lock button. FIG. 2 is a right-side view of the leash housing of FIG. 1. FIG. 3 is an isometric view of the leash housing of FIG. 1, the figure showing a gate closed and a leash gate lock in a locked position.

FIG. 4 is a top view of the leash housing of FIG. 1. FIG. 5 is a front plan view of the leash housing of FIG. 1, the figure showing the leash housing an optional stop button and lock button.

FIG. 6 is an isometric view of the leash housing of FIG. 1, the figure showing a gate opened and a leash gate lock in an unlocked position.

FIG. 7 is a right-side view of the leash housing of FIG. 1 the figure showing a gate opened and a leash gate lock in an unlocked position; and,

FIG. 8 is an isometric view of the leash housing of FIG. 1, the figure showing a gate opened and a leash gate lock in an unlocked position.

The broken lines shown in the drawings illustrate features that are not claimed, and form no part of the claimed design.

1 Claim, 8 Drawing Sheets
